[57] CLAIM

The ornamental design for lavatory, as shown and described.

DESCRIPTION

FIG. 1 is a top plan view of a lavatory showing my new design;

FIG. 2 is a left side elevational view thereof, the right side being a mirror image of the left side;

FIG. 3 is a front elevational view thereof;

FIG. 4 is a rear elevational view thereof;

FIG. 5 is a bottom plan view thereof;

FIG. 6 is a top plan view of a second embodiment thereof;

FIG. 7 is a front elevational view of FIG. 6;

FIG. 8 is a left side elevational view of FIG. 6, the right side being a mirror image of the left side;

FIG. 9 is a rear elevational view of FIG. 6;

FIG. 10 is a bottom plan view of FIG. 6;

FIG. 11 is a cross sectional view taken on line 11—11 of FIG. 1; and,

FIG. 12 is a cross sectional view taken on line 12—12 of FIG. 6.

The characteristic feature of my design for sanitary-ware and the like resides in the three-dimensional striping of the finished layer.
